UNITED STATES PATENT OFFICE.

JOSEPH S. REID, OF OLEAN, NEW YORK, ASSIGNOR TO CLARK BROTHERS COMPANY,
A CORPORATION OF NEW YORK.

SAWMILL CARRIAGE.

Application filed April 17, 1924. Serial No. 707,195.

To all whom it may concern:

Be it known that I, JOSEPH S. REID, a citizen of the United States, residing at Olean, in the county of Cattaraugus and 5 State of New York, have invented certain new and useful Improvements in Sawmill Carriages, of which the following is a specification.

This invention relates to saw mill carriages, more particularly to the means for feeding the knees transversely of the carriage, the object of the invention being to so construct the knee feed nut that it may be adjusted to take up the wear between it and 15 the feed screw.

In the accompanying drawings:

Fig. 1 is a transverse sectional view through the saw mill carriage;

Fig. 2 is a vertical section through the 20 feed screw taken on line 2—2 of Fig. 1; and,

Fig. 3 is an enlarged sectional view through the feed nut.

The numeral 1 indicates the carriage mounted upon suitable trucks 2. Arranged 25 to travel transversely of the carriage is a knee 3 actuated by a feed screw 4. Journaled at its outer end is a suitable bearing 5. The outer end of the feed screw 4 is provided with a pinion 6 adapted to mesh with 30 a pinion 7 keyed to a drive shaft 8, extending lengthwise of the machine and geared to the actuating mechanism of the several knees.

To compensate for the taper of the log, 35 means are provided for the manual adjustment of the several knees independently of the mechanical feeding means common to all of the knees. To accomplish this, I preferably provide the following construction:

40 The numeral 9 indicates a lever pivoted as at 10 in the knee 3.

A feed nut 12 engaging the feed screw 4 is preferably made into upper and lower parts 13 and 13', the upper half being provided with upwardly projecting lugs 14—14 which are connected to the lower end of the taper lever 9 by links 11—11 pivotally connected thereto by means of a pin 10', the opposite ends of the links being pivotally connected to the feed nut lugs 14—14 by means 50 of a pin 11', whereby the horizontal movement of the feed-nut 12 is imparted to the knee 3.

The lower half 13' of the unit is bolted to 55 the upper half 13 of the nut by a suitable

bolt 15, with a sufficient clearance for the bolts in the upper half 13 to permit of a longitudinal adjustment of the respective halves of the nut. To accomplish this adjustment the lower half 13' of the nut is 60 provided with an upwardly projecting ear 16 adapted to receive a bolt 17 carried by a transverse lug 18 of the upper half of the nut, having interposed between the ear 16 and the lug 18 a plurality of metal liners 65 19. By removing one or more of these liners, wear in the threads of the nut and the screw may be taken up. The threads may be cut in the upper and lower halves of the nut, but preferably the upper and lower halves 70 13 and 13' are of cast steel with a cored chamber 20, the cored chamber to contain a lining of babbitt 21, which is cast in the unit to fit the thread screw.

The upper half of the nut is preferably 75 provided with front and rear laterally extending lugs 23—23, adapted to be received in suitable horizontal grooves, 24—24, arranged in the lower portion of the knee 3.

As a means for adjusting the quadrant 80 25 which the taper lever 9 engages, I preferably provide adjusting screws 26 and 27 at the outer ends of the quadrant 25, by means of which the base of the knee can be moved slightly ahead or backward with reference 85 to the knee screw nut, for aligning the several knees.

To prevent the log from slipping on the carriage, I provide each knee with a plurality of pivoted dogs 30 aligned vertically 90 between the vertical side walls of the knee 3, the several dogs being connected together by a vertically arranged link 31. One of the several dogs 30 is connected by a horizontal link 32 to an actuating lever 33 journaled upon the shaft 10. 95

I claim:

1. The combination of a base, a bearing, a feed screw journaled in said bearing, a knee, a feed nut carried by said knee, comprising upper and lower halves bolted together, and internally screw-threaded to receive said feed screw, and means for adjusting the upper and lower halves of said feed nut longitudinally with respect to each 105 other.

2. The combination of a base, a bearing, a feed screw journaled in said bearing, a knee adjustable upon said base, a feed nut carried by said knee and actuated by said 110

feed screw, said feed nut comprised of upper and lower halves internally screw threaded, lugs projecting laterally from the upper and lower halves of the nut, having aligned openings one of which is of greater diameter than the other and a bolt received in said openings whereby the upper and lower halves of the nut may be adjusted longitudinally relative to each other.

3. The combination of a base, a bearing, a feed screw journaled in said bearing, a knee adjustable upon said base, a feed nut carried by said knee and actuated by said feed screw, said feed nut comprised of upper and lower halves internally screw threaded, lugs projecting laterally from the upper and lower halves of the nut, having aligned openings, transversely of the axis of the bearing, one of which is of greater diameter than the other, lugs extending transversely from the two halves of the bearing, and provided with aligned openings longitudinally of the axis of the bearing, and a bolt received in said openings whereby the upper and lower halves may be adjusted longitudinally with respect to each other.

4. The combination of a base, a bearing carried thereby, a feed-screw journaled in said bearing, a knee adjustable upon said base, a feed-nut comprising upper and lower halves bolted together and internally screw-

threaded to receive said feed-screw, means for adjusting said upper and lower halves with respect to each other longitudinally of the feed-screw, a quadrant lever connected 35 with said screw-feed, links connecting said quadrant lever in said feed-knee, and means for adjusting said quadrant relative to said knee.

5. The combination of a base, a bearing 40 carried thereby, a feed-screw journaled in said bearing, a knee adjustable upon said base, a feed-nut comprising upper and lower halves bolted together and internally screw-threaded to receive said feed-screw, lugs 45 projecting laterally from the upper and lower halves of the nut having aligned openings transversely of the axis of the bearing, one of which is of greater diameter than the other, lugs extending transversely 50 from the two halves of the bearing and provided with aligned openings longitudinally of the axis of the bearing, and a bolt received in said openings whereby the upper and lower halves may be adjusted longitudinally with respect to each other, a quadrant lever carried by said knee, links connecting said quadrant lever and said feed nut, and means for adjusting said quadrant 55 relative to said knee.

In testimony whereof I affix my signature.

JOSEPH S. REID.
